CLAIM

The ornamental design for a power converter body, as shown and described.

DESCRIPTION

FIG. 1 is a perspective view of a power converter body.

FIG. 2 is a top plan view thereof.

FIG. 3 is a bottom plan view thereof.

FIG. 4 is a right side elevational view thereof.

FIG. 5 is a left side elevational view thereof.

FIG. 6 is a front elevational view thereof.

FIG. 7 is a rear elevational view thereof.

FIG. 8 is a perspective view of a power converter body with broken lines illustrating environment (e.g. electrical contact areas) that is not part of the design.

FIG. 9 is a top plan view thereof.

FIG. 10 is a bottom plan view thereof.

FIG. 11 is a right side elevational view thereof.

FIG. 12 is a left side elevational view thereof.

FIG. 13 is a front elevational view thereof.

FIG. 14 is a rear elevational view thereof.

FIG. 15 is a perspective view of a power converter body with broken lines illustrating environment (e.g. a ball grid array) that is not part of the design.

FIG. 16 is a top plan view thereof.

FIG. 17 is a bottom plan view thereof.

FIG. 18 is a right side elevational view thereof.

FIG. 19 is a left side elevational view thereof.

FIG. 20 is a front elevational view thereof; and,

FIG. 21 is a rear elevational view thereof.

The stippling in each embodiment indicates a contrasting color (e.g., black or dark gray or another color) of the stippled portion of the design relative to the color (e.g., metallic color or light gray or another color) of the non-stippled portion of the design.
